UNITED STATES PATENT OFFICE.

DANIEL X. KELLY, OF ST. LOUIS, MISSOURI.

AEROPLANE.

1,312,548.

Specification of Letters Patent.

Patented Aug. 12, 1919.

Application filed June 17, 1918. Serial No. 240,322.

To all whom it may concern:

Be it known that I, DANIEL X. KELLY, a citizen of the United States, and resident of St. Louis, State of Missouri, have invented certain new and useful Improvements in Aeroplanes, of which the following is a specification containing a full, clear, and exact description, reference being had to accompanying drawings, forming a part 10 thereof.

My invention relates to improvements in aeroplanes, and has for its object to provide an aeroplane with stabilizers whereby the lateral as well as the longitudinal stability 15 of an aeroplane may be maintained, and to provide automatic longitudinal stability when the operator of the plane loses control or becomes disabled.

A further object is to provide the wings 20 and tail of an aeroplane with stabilizers which may operate either manually or automatically, and a further object is that when it is desired to land, and the operator removes his foot from the manual controlling 25 means, the automatic means will tend to straighten out the machine and cause it to land on an even keel.

In the drawings,

Figure 1 is a view of a portion of an aeroplane, showing the operating levers and one 30 of the main stabilizers in position.

Fig. 2 is a cross sectional view of one of the main stabilizers, showing the automatic control.

Fig. 3 is an end view of one of the main stabilizers and its connecting mechanism, in horizontal position, with the tilted positions being shown by dotted lines.

Fig. 4 is a vertical cross sectional view 40 through the main stabilizer bearing.

Fig. 5 is a sectional view taken on the line 5-5 of Fig. 4, viewing same in the direction of the arrow.

Fig. 6 is a view of the manual operating 45 device in lowered or disconnected position.

Fig. 7 is a view of the tail stabilizer, showing its connection to the main stabilizer.

Fig. 8 is a horizontal cross sectional view 50 of the tail stabilizer showing the manner of mounting the same.

Fig. 9 is a perspective view of the elevating means and quadrant for the manual control of the stabilizers.

55 Fig. 10 is a perspective view of the ele-

vating means for throwing the stabilizers into manual operative position.

Fig. 11 is a diagrammatical view, showing the aeroplane in horizontal position, and showing the "tail spin" in light dotted lines 60 and the "nose dive" in heavy dotted lines, and the position the stabilizers assume when operating automatically.

In carrying out my invention I provide a framework 12. This framework may be 65 so constructed as to constitute either a bi-plane or a tri-plane. This framework is provided with main or supporting planes 13. At the outer edge of these main planes I provide a main stabilizer 14, which is mounted on a shaft 15. This shaft is supported in bearings 16 and 17. The bearings 17 are composed of two parts 18 and 19, the parts 18 and 19 having horizontal portions 21, and between these horizontal portions, rollers 22 are inserted so as to allow free movement of the main stabilizing planes 14.

The end 23 of the shaft 15 is supported by truss rods or wires 24, which are attached to collars 25 located near the outer end of 80 the shaft 15 and collars 26 which are located near the inner end of the shaft 15. The truss rods or wires 24 pass through wall 27 formed on the part 19 of the bearings, and the tension on these truss rods is regulated by the turn buckles 28.

On the inner end of the shaft 15 I provide a gear 29. This gear is adapted to mesh with teeth formed on a segment 30. The segment 30 is provided at its lower 90 end with a lever 31, and to the lower end of this lever is attached a pivot 32 which operates through a slot 33 formed in a lever 34. This lever is rigidly attached to a shaft 35, and is operated by means of a lever 36, 95 which may be locked in any desired position on the quadrant 37 by means of the catch 38.

The quadrant 37 is integrally formed with a bar 39, this bar 39 serving the purpose of placing the segment 30 into and out of engagement with the gear 29. The bar 39 is provided near its upper end with an opening 40, to which the segment 30 is pivotally attached by means of a bolt or rivet 41. The bar 39 is further provided with slots 42, 100 which secure it to an upright plate 43, this plate also serving as the interior bearing for the shaft 15. Near their lower ends the bar 39 and the quadrant 37 are provided with openings 44, through which shaft 35 105 110

projects. To this shaft 35 the levers 34 and 36 are rigidly attached so that any movement of the lever 36 will be transmitted to the lever 34.

5 In order to elevate my device, I provide a shaft 51, which is provided with a foot lever 52 and a pair of cam levers 53. The object of this construction is that when the foot is placed upon the lever 52, and pressed 10 downwardly, the cam levers 53 will raise the bar 39, throwing the segment 30 into engagement with the wheel 29 and placing my device in manual operation.

On the shaft 15 is mounted a lever 54, 15 which is connected to a lever 55 mounted on a shaft 56. This shaft 56 is rigidly connected to the tail 57 of the aeroplane by means of the sleeve 58 and the pin 59, which extends through the sleeve and the shaft.

20 The tail stabilizer 60 is loosely mounted on the shaft 56 by means of the bearings 61 and 62. The side shifting of the tail stabilizer is prevented by means of collars 63 and on the bearings 61 is attached the lever 55. 25 Connecting the levers 54 and 55 I provide wires or rods 64. These wires or rods are provided with turn buckles 65; the object of these turn buckles being to act as a slack take up between the main stabilizer and the tail 30 stabilizer, and to adjust the stabilizers in the same horizontal plane.

In each main stabilizer, and secured to the shaft 15 I mount a weight 66. This is secured to the shaft by means of a collar 67 35 having a dependent screw threaded shank 68. On this screw threaded shank 68 I provide a weight 69, which is held in any desired position on the shank by means of nuts 70. By this means I regulate the sensitivity

40 of the stabilizers, as it will be readily understood that, when my device is tilted and if the weight is raised to its uppermost position, the weights controlling the stabilizing planes will not be operated through 45 as great an arc to resume their vertical position as when the weights are nearer the lower end of the depending shank; in other words, the stabilizing planes will respond quicker when the weight is raised than when 50 it is lowered.

It will, of course, be understood that each side of the machine is provided with a main stabilizer and a stabilizer for the tail. The main stabilizer on one side of the machine 55 and the stabilizer on the tail are operated simultaneously and independently from the main stabilizer and tail stabilizer on the opposite side of the machine. Both pairs of stabilizers and their operating means are 60 constructed alike, and as previously described. Both pairs of stabilizers on both sides of the machine operate simultaneously when the foot of the operator is removed 65 from the foot lever 52. In other words, both pairs of stabilizers are automatically oper-

ated simultaneously, and are capable of being manually operated independently of each other.

It will be further understood that the stabilizers not only perform the function of stabilizing the machine, but also act as supporting surfaces in addition to the supporting plane or planes.

The machine is steered by an ordinary rudder 71 operated in a manner well known to the art, and underneath the main supporting planes is placed a running gear 72 and the tail supported by a single wheel or skid 73; this construction being old and in common use in aeroplane construction, and therefore I have not described the matter in detail.

The operation of my device is as follows: The operator or aviator having taken his seat, places one foot on the lever 52, raising the manual stabilizer and throwing the segment 30 into engagement with the gear 29. When in this position, by moving the levers 36 in opposite directions, the plane can be set or tilted to any lateral angle desired, and especially by use of the small stabilizing planes at the rear of the machine. When making a "nose dive" or a "tail spin", the operator is in full control of the machine, and a gentle landing will be made.

In the event that the operator loses control of the machine, all that is necessary is to remove the foot from the lever 52, and the automatic control will come into action, and again, if the operator be wounded and collapse in his seat, it is almost positive that his foot will slip off of the lever 52, thereby setting the automatic control into action, and preventing the smashing of the machine when alighting.

It will be observed, from the foregoing description, that when the foot of the operator is removed from the foot lever 52, the manual operating mechanism is disengaged from the gear 29, thus permitting the gravity control to act on the stabilizing planes, which will tend to maintain them in a horizontal position, which tends to preserve the longitudinal stability of the machine.

When the manual operating mechanism is in engagement with the gear 29, the main stabilizing planes on each side of the machine may be operated so as to preserve the lateral stability of the machine. The manual operation is for the purpose of maintaining both longitudinal and lateral stability, and the gravity control is for the purpose of maintaining longitudinal stability.

While I have illustrated my invention as applied to a tri-plane, the principle thereof may be applied to either a mono-plane or a bi-plane.

In the event the operator loses control of the machine while in the air, it is only neces-

sary for him to remove his foot until the automatic stabilizing apparatus has again put the machine onto an even plane or keel, and then by resting his foot on the lever 52, the 5 manual operating means is again thrown into action.

Having fully described my invention, what I claim is:—

1. An aeroplane comprising a main body 10 frame and a tail frame, supporting planes carried by the main body frame, a pivoted stabilizing plane mounted adjacent to each end of the supporting planes, a stabilizing plane mounted on each side of the tail frame 15 adjacent its rear end, a connection between the tail stabilizers and main stabilizers, means for manually operating the pair of stabilizers on each side of the machine simultaneously with each other and independently 20 from the pair of stabilizers located on the opposite side of the machine, means for placing the manual operating mechanism in and out of connection, and gravity controlled means for operating the 25 stabilizers in pairs on each side of the machine.

2. An aeroplane comprising a main body portion provided with supporting planes and a tail portion extending in the rear of 30 said body portion, a stabilizing supporting plane mounted on each end of the main body portion adjacent the supporting planes carried thereby, pivoted stabilizing planes carried by the tail portion, an adjustable flexible connection between the stabilizing planes carried by the tail and those carried by the main body portion connecting them in pairs, manually controlled means for operating 35 one of the main stabilizers located at one end 40 of the body portion of the machine and one of the stabilizers carried by the tail portion simultaneously, a foot lever for operatively connecting the manually controlled means with the stabilizers, and gravity controlled 45 means for operating the stabilizers when the manually controlled means are disengaged therefrom.

3. An aeroplane comprising a main frame, a tail frame attached to the main frame, supporting planes carried by the main frame, stabilizers pivotally mounted at the extreme outer edge of the supporting planes, stabilizing planes mounted on each side of the tail frame and near its rearmost end, adjustable, 50 flexible connections connecting the stabilizing planes on each side of the machine in pairs, means for manually controlling each pair of stabilizers independently of each other, means for engaging and disengaging the 55 manually controlled means, and adjustable gravity controlled means for operating the stabilizers in pairs.

4. An aeroplane comprising supporting planes and a tail attached thereto, stabilizers 60 attached at each end of the supporting

planes, and near the rear end of the tail, means for connecting the stabilizers on each side of the machine together in pairs, manual means for operating the pair of stabilizers on either side of the machine in the 70 same direction simultaneously, means for connecting and disconnecting the manual means to the stabilizer.

5. An aeroplane comprising a main body frame and a tail frame, supporting planes 75 carried by the main body frame, a pivoted stabilizing plane mounted adjacent to each end of the supporting planes, a stabilizing plane mounted on each side of the tail frame adjacent its rear end, a connection between 80 the tail stabilizers and main stabilizers, means for operating both stabilizers on each side of the machine simultaneously with each other and independently from the stabilizers located on the opposite side of the 85 machine, means for locking the stabilizers in position when manually controlled, and a foot lever for placing the stabilizers into and out of automatic operation when de- 90 sired.

6. An aeroplane comprising a main body frame and a tail frame, supporting planes carried by the main body frame, pivoted stabilizing planes mounted adjacent each end of the supporting planes, a stabilizing 95 plane mounted on each side of the tail frame adjacent its rear end, an adjustable connection between the stabilizers on each side of the machine connecting them in pairs, weights for controlling the action of each 100 pair of stabilizers by gravity, and a lever mechanism for manually operating the pairs of stabilizers manually and independently of each other.

7. An aeroplane comprising a main body 105 frame and a tail frame, supporting planes carried by the main body frame, pivoted stabilizing planes mounted adjacent each end of the supporting planes, a stabilizing plane mounted on each side of the tail frame 110 adjacent its rear end, an adjustable connection between the stabilizers on each side of the machine, weights for controlling the action of the stabilizers by gravity, a lever mechanism for operating the stabilizers 115 manually, and means for throwing the manual control into and out of operation.

8. An aeroplane comprising a main body frame, a supporting plane carried thereby, a stabilizing plane pivotally carried at each 120 end of the supporting plane, manual means for operating the stabilizing plane, a foot operated means for engaging and disengaging the manually operated means with the stabilizing planes, and a gravity means for 125 operating said plane independently of the manual operated means.

9. An aeroplane comprising a main body frame, a supporting plane carried thereby, a stabilizing plane pivotally carried at each 130

end of the supporting plane, manual means for operating the stabilizing plane, a foot operated eccentric means for engaging and disengaging the manually operated means 5 with the stabilizing planes, and a gravity means for operating said plane independently of the manual operated means.

10. An aeroplane comprising a main body frame, a supporting plane carried thereby, a 10 stabilizing plane pivotally carried at each end of the supporting plane, manual means for operating the stabilizing plane, a foot operated eccentric means for engaging and

disengaging the manually operated means with the stabilizing planes, a gravity means 15 for operating said plane independently of the manual operated means, and a quadrant for locking the stabilizers in any desired position.

In testimony whereof I have signed my 20 name to this specification in the presence of two subscribing witnesses.

DANIEL X. KELLY.
